CATALYTIC CRACKING PROCESS

Conrad H. Kollenberg, Goose Creek, Tex., assignor to Standard Oil Development Company, a corporation of Delaware

Application June 5, 1943, Serial No. 489,734

2 Claims. (Cl. 196—52)

The present invention relates to a method for cracking hydrocarbon oils in the presence of a powdered solid catalyst. More particularly, it is concerned with the reduction and/or the prevention of coke deposits on the powdered solid during the cracking of the hydrocarbons.

One of the more important features of catalytic cracking processes employing the fluid or powdered catalyst technique, in which the finely divided catalyst moves along with the oil flowing through the reaction system and after reaction is completed is separated and regenerated in a zone outside of the reaction system, is the regeneration of the spent catalyst. Deposition of coke and tarry material on the finely divided powder increases the amount of burning necessary in the regeneration system and consequently reduces the throughput of a given unit when the amount and degree of regeneration of catalyst becomes greater than the facilities can care for.

It is usual practice in most catalytic cracking operations employing the powdered catalyst technique to withdraw from the primary fractionating zone a slurry of oil and catalyst for recycling to the reaction system. A small amount of powdered catalyst is always carried over into the primary fractionating zone with the vapors leaving the cyclone, operating immediately ahead of the primary fractionating zone. This small amount of catalyst is concentrated in the heavier fractions of the oil in the fractionating zone by washing in the bottom section thereof and is carried out with the heavy oil fraction which remains from the distillation. This heavy oil, being subjected to repeated recycling and conversion, is highly aromatic in nature and has been found to contribute largely to the formation of carbonaceous deposits on the catalyst particles in the reaction zone. Efforts have been made in the past to reduce the amount of coke formed on the catalyst by filtering out the residual oil remaining in the catalyst. As will be recognized by those skilled in the art, this expedient requires special equipment which is expensive and sometimes unavailable.

It has now been discovered that the catalytic cracking operation may be improved so that the amount of coke deposited on the catalyst in the reactor system is reduced to a minimum by substituting for the aromatic oil withdrawn from the bottom of the fractionation zone a highly paraffinic oil having a boiling range above the boiling range of the feed oil to the cracking system. This expedient obviates the formation of coking particles on the finely divided powder used as a catalyst. In the practice of this invention the aromatic oil which has been found to be the main source of trouble is distilled out in the primary fractionating system and is withdrawn as a heavy

oil side-stream fraction and a highly paraffinic oil is substituted therefor.

More specifically, the invention comprises adding to the bottom of the primary fractionating zone of a powdered catalyst cracking operation a petrolatum fraction obtained from a crude petroleum which is highly paraffinic in nature. One specific feature of the present invention is to introduce the paraffinic oil into the bottom of the fractionating tower continuously with substantially all of the products of cracking being continuously distilled out, so that the amount of aromatic constituents recycled to the reaction system is maintained at a minimum.

15 The amount of petrolatum added to the bottom of the primary fractionating zone will vary depending on the capacity of the particular unit. Generally for a catalytic cracking unit charging between 10,000 and 15,000 barrels per day of feed oil, about 300 to 1,000 barrels per day of the paraffinic petrolatum should be added. A like amount of aromatic slurry oil should be discarded. Depending again on the size of the unit, the amount of powdered catalyst carried over from the cyclone immediately ahead of the primary fractionating zone will vary directly with the unit capacity; about 2 to 5 tons per day will carry over from the cyclone and be recycled from the bottom of the primary fractionating zone in a unit of the size mentioned above.

20 25 30 35 40 45 50 55 60 65 70 75 80 85 90 95 The paraffinic petrolatum oils employed are characterized by having a boiling range higher than that of the feed to the cracking system. The characteristics of an oil giving good results is compared with the aromatic slurry oil in the following table:

Table I

	Petrolatum	Aromatic slurry oil
Gravity, °API.....	28.8	14.2
Distillation at 10 mm. pressure:		
IBP °F.....	355	243
5% at °F.....	620	344
10% at °F.....	(1)	391
95% at °F.....		616

¹ Cracked.

The conditions employed in the reaction system of the process of the present invention will vary depending on the charge stocks employed but generally will range from about 850° to 1000° F. with pressures of about 10 to 20 lbs./sq. in. The temperature in the bottom of the primary fractionating zone will range in the neighborhood of 550° to 650° F. and will require the injection of an oil a considerable percentage of which boils above the foregoing temperature at the partial pressure in the tower. As mentioned before, this desirable boiling range is embodied in petrolatum fractions from paraffinic crudes.

The present invention will be better understood by reference to the drawing in which the single figure is a front elevation in diagrammatic form of the portion of a catalytic cracking process with which the present invention is concerned. It is to be understood that the cracking unit will embody other necessary equipment.

Referring now to the drawing, numeral 11 represents a pipe line carrying vaporized heated hydrocarbons from a superheater not shown. Regenerated catalyst from a powdered catalyst regenerating system (not illustrated) is introduced into line 11 by way of line 12 in which a suspension of powder in vaporized oil is maintained. There is also injected into line 11, by way of line 13, a slurry of oil and catalyst withdrawn from the bottom of fractionating zone 14 which will be described in further detail hereinafter.

The combined streams of catalyst and oil are injected into reactor zone 15 by way of line 11 and are passed therethrough at a rate allowing a sufficient retention time for reaction to be completed.

The stream of powdered catalyst and cracked hydrocarbons leaving reactor 15 by way of line 16 is injected into cyclone separator 17 which is connected directly to spent catalyst hopper 18 in the manner shown. Cyclone 17 is a means for separating powdered catalyst from the vaporized oils in a manner well known in the art.

The vaporized hydrocarbons leaving cyclone 17 by way of line 19 are injected thereby into fractionating zone 14 while spent catalyst is withdrawn from spent catalyst hopper 18 through line 20 for regeneration in a regeneration stage not shown in the drawing.

The vaporized hydrocarbons injected into fractionating zone 14 by way of line 19 contain a small percentage of the powdered catalyst not separated from the hydrocarbons in cyclone 17. In usual operations, the powdered catalyst will comprise less than about 0.1% by weight of the vaporized hydrocarbons injected into the fractionating zone 14, it being impractical to obtain absolute separation of the catalyst and vaporized hydrocarbons in cyclone 17.

Fractionating zone 14 comprises all the usual equipment required to separate hydrocarbons by distillation and may include one or more distillation towers. Fractionating zone 14 is provided with line 21 for removal of fractions boiling below 400° F., with line 22 for withdrawal of the heating oil fraction boiling between about 400° and 600° F., and with line 23 for withdrawal of the gas oil fraction boiling in the range of about 550° to 850° F. A heavier fraction is discharged from fractionating zone 14 by way of line 24.

Connected to line 24 is line 25 in direct communication with storage tank 26 which contains a petrodatum oil fraction obtained from a crude petroleum of paraffinic nature. Located in line 25 is pump 27 for transferring the paraffinic oil from tank 26 by way of line 25 into line 24.

Line 24 connects into line 13 to allow recycling of the oil fraction withdrawn from the bottom of fractionating zone 14 by way of line 24 to line 11 connecting to reactor zone 15. In this manner the catalyst carried over from cyclone 17 into fractionating zone 14 is returned to the reaction system along with the oil remaining after distillation of the aforementioned fractions.

It was at this point, prior to the practice of the present invention, that the aforementioned difficulties were encountered in recycling the slurry oil to reactor zone 15. Prior to the present in-

vention, the oil circulated by way of lines 24 and 13 to line 11 was highly aromatic in nature and caused deposition of coke upon the catalyst in the reaction zone. By introducing a high boiling

5 paraffinic oil through line 25 into line 24 and by recycling a part of the effluent from line 24 through line 28 into fractionating tower 14, the highly aromatic fractions are caused to be distilled out with the gas oil fraction through line 23.

10 It will be understood by persons skilled in the art that the oil recycled through line 28 may be introduced at any suitable point in tower 14. However, in the modification shown in the drawing, it is assumed that the vapors entering tower 15 14 through line 19 are highly superheated. Hence, by cooling the oil recycled through line 28 in cooling means 29 and introducing this cooled oil into tower 14 at a point above the entrance of line 19, it is possible to remove much of the superheat and provide a stripping action in the bottom of the distillation tower.

Other modifications will occur to those skilled in the art without departing from the spirit of the invention. Thus, when the vapors in line 25 19 are not highly superheated, the oil withdrawn through line 24 and recycled through line 28 may be passed through a heating means provided in place of cooler 29 and introduced into tower 14 at a point below the entrance of line 19.

30 It will thus be seen in the foregoing description that the essence of the present invention resides in the continuous discarding of the deleterious heavy aromatic fractions and the continuous injection of an oil which does not crack into cokey material to as great an extent as the aromatic oil for which it was substituted.

The nature and objects of the present invention having thus been described and illustrated, what I desire to claim as new and useful and to

40 secure by Letters Patent is:

1. In a catalytic cracking process in which a finely divided catalyst is carried in suspension in oil vapors through a cracking zone and some of such catalyst is carried over by the vaporous products from said cracking zone into a subsequent fractionating zone, the steps of introducing into said fractionating zone a paraffinic oil having a boiling range substantially above that of the highest boiling components of said vaporous products, taking off said latter components at an intermediate point from said fractionating zone, taking off from the bottom of said zone a suspension of catalyst in said paraffinic oil and conducting said suspension to the cracking zone.

55 2. In a catalytic cracking process in which a finely divided catalyst is carried in suspension in oil vapors through a cracking zone and some of such catalyst is carried over by super-heated vaporous products from said cracking zone into a subsequent fractionating zone, the steps of

60 introducing into said fractionating zone at a point above the point of introduction of said super-heated vapors a paraffinic oil having a boiling range substantially above that of the highest boiling components of said vaporous product, taking off said latter components at an intermediate point from said fractionating zone above the point of introduction of said paraffinic oil, continuously withdrawing a suspension of catalyst in said paraffinic oil from the bottom of said zone, continuously passing a portion of said suspension through a cooling zone and returning it to said fractionating zone and continuously conducting a portion of said suspension to the cracking zone.
